Specification for Design.

Patented Aug. 9, 1921.

Application filed March 19, 1921. Serial No. 453,757. Term of patent 14 years.

To all whom it may concern:

Be it known that we, OSCAR H. PIEPER and ALPHONSE F. PIEPER, both citizens of the United States, residing at Rochester, in the county of Monroe and State of New York, have invented a new, original, and ornamental Design for a Casing for Electric Switches, of which the following is a specification, and of which the accompanying drawing is a representation.

Figure 1 is a front view of a casing for an electric switch, showing our new design; and Fig. 2 is a side view of the same.

We claim:

The ornamental design for a casing for electric switches, as shown.

OSCAR H. PIEPER.
